UNITED STATES PATENT OFFICE.

AMEDEO A. MANCINI, OF BROOKLYN, NEW YORK.

TIME-LOCK.

1,347,047.

Specification of Letters Patent.

Patented July 20, 1920.

Application filed October 7, 1919. Serial No. 329,127.

To all whom it may concern:

Be it known that I, AMEDEO A. MANCINI, a subject of the King of Italy, residing at the borough of Brooklyn, in the city of New York, county of Kings, and State of New York, have invented certain new and useful Improvements in Time-Locks, of which the following is a specification, reference being had therein to the accompanying drawings, 10 which form a part thereof.

My invention relates to time locks; and more particularly to a type thereof wherein a clock works controls the bolt actuating mechanism, the lock of my invention being 15 adapted for use alone or in connection with the ordinary permutation lock.

In a lock made in accordance with my invention, the locking means for the bolt actuating mechanism is so constructed that it has 20 a normal tendency to engage and lock said mechanism immediately that the bolts are shot, and will be automatically retracted to permit the actuation of said mechanism at predetermined intervals as determined by 25 the releasing mechanism controlled by the clock works. The releasing mechanism itself may be so set as to insure its action upon the locking member at different desired intervals. Furthermore this releasing mechanism, 30 in withdrawing the locking member, is actuated from a source of power independent of the clock works, so that in the event of the disarrangement of the clock works as a result of external shocks upon the door 35 carrying the lock, if continued rapid movement of the clock works and the releasing mechanism should result, the speed attained by said releasing mechanism will be sufficiently high to avoid withdrawal of the locking member for a sufficient interval to permit the actuation of the bolt mechanism. If 40 continuous pressure be applied to the knob spindle so as to withdraw the bolt during the brief interval when the releasing mechanism 45 is operative under the conditions above referred to, this pressure under ordinary conditions will develop such friction between said locking member and the support therefor, and between said actuating means and 50 said locking member, to prevent movement of the releasing mechanism to effect the release of said locking member.

While, when the actuating mechanism has been actuated to withdraw the bolts, the con-

dition will be such as to prevent the locking member becoming operative as to this mechanism until the bolts are again shot, I provide supplemental means operative upon said locking member which may be so set as to maintain said member inoperative as to the actuating means, thus permitting the instantaneous locking of the door at any time by the mere turning of the knob, which is desirable in the case of an emergency, or preventing the accidental locking of the door through the time lock mechanism.

The locking member is so constructed and supported as to withstand any forcing stresses applied to it through the actuating mechanism, and prevents such stresses being transmitted to other mechanisms of the lock.

While a single clock works mechanism and a single releasing mechanism may be employed, it is possible, and sometimes preferable, to duplicate such mechanisms and have them act simultaneously upon the actuating mechanism locking member, so that in the event of the failure of one clock works to properly function, the other will nevertheless continue to act. It is also possible to so set the releasing mechanism associated with the different clock works, to insure their successive actuation, thus providing a predetermined interval so that the locking member will be actuated twice during a brief lapse of time, thus permitting the opening of a door after a short predetermined interval in the event that the door is not opened when the first releasing mechanism operates upon the locking member, or is due to operate thereon in the event that it fails to so operate.

The invention consists in the novel features of construction and combination of parts hereinafter set forth and described, and more particularly pointed out in the claims hereto appended.

Referring to the drawings,

Figure 1 is a vertical section through the casing of the time lock mechanism, disclosing the various mechanisms in elevation;

Fig. 2 is a rear view thereof with the closure plate removed;

Fig. 3 is a view illustrating the device in connection with a safe door;

Fig. 4 is a detail view of one of the bolt mechanisms;

Fig. 5 is a rear view of the lock mechanism

shown in Fig. 1, upon a reduced scale with the back closure plate secured to the casing;

Figs. 6 and 7 are respectively a front and side view of the plate of the actuating mechanism;

Figs. 8 and 9 are detailed views of intermediate gears of the train connecting the clock works with the releasing wheel;

Fig. 10 is a detail view of the end of the setting shaft;

Fig. 11 is a side and projected end view of one of the actuating cams carried by the releasing wheel; and

Fig. 12 is a view of the invention in a form employing single clock works and a single releasing mechanism actuated thereby.

Like letters refer to like parts throughout the several views.

In the form of the invention shown in the drawings, the time lock mechanism is mounted in a casing A adapted to be mounted upon a door in any desired manner, said casing being closed by means of the plate A', having openings therein through which portions of the bolt actuating mechanism may be observed when the door is open. Mounted within the casing A is a bolt actuating mechanism consisting of a plate a having pivoted thereon, adjacent the periphery thereof, a plurality of links a', a² and a³, each of which links is pivotally connected to a bolt structure as a⁴, shown in detail in Fig. 4 of the drawings. The detailed construction of this bolt structure is immaterial to this invention, as any desired number and arrangement of bolts may be employed.

The plate a is carried by and rotatable with a spindle b which projects through the casing and the door carrying the casing, and is equipped with the usual handle or knob b'.

Said plate a is so constructed as to have a limited turning movement in one direction to withdraw the bolts, and a return movement to the same extent to project the bolts, the time controlled lock mechanism being operative upon this plate to prevent movement thereof during that interval when it is desired to prevent the actuation of said plate and the bolts controlled thereby.

The means limiting the movement of said plate a to that required to retract or to shoot the bolts, consists of a heavy rod c carried by the casing A and its closure plate A', and projecting through a segmental opening c' in the plate a. One end of said opening c' is enlarged as at c² to receive the locking member operative upon the plate a, this enlargement being at the end of said slot which is adjacent the rod c when the bolts are shot.

Slidably mounted upon the rod c is a locking member d, the diameter of which is sufficiently great not to enter the segmental slot c', but sufficiently small to freely enter the

enlargement c² of said slot. Acting upon the member d, with a normal tendency to force it toward the plate a, is a spring d'. The member d is provided with a lug d² secured to which is a stem d³ projecting through the closure A' and provided with an actuating knob d⁴ exposed exteriorly of said closure. Said knob d⁴ is rotatably mounted upon the stem d³ which knob carries a stop pin d⁵ adapted to enter an opening d⁶ in said closure. By this construction the member d will at all times be held against rotation by the stem d³, it being possible, by bringing the pin d⁵ out of register with the opening d⁶, to prevent the spring d' acting upon the member d, and thus avoid the premature locking of the member a in the event of the accidental shooting of the bolt during that time when it is desired not to lock the door carrying the lock mechanism.

Coöperating with the locking member d is a releasing mechanism or releasing mechanisms controlled by suitable clock works so that said member will be automatically withdrawn from its operative relation to lock the plate a at predetermined intervals. In Figs. 1, 2 and 5 I have illustrated a lock employing two releasing mechanisms of this character, while in Fig. 12 I have illustrated a lock employing but one such mechanism. When but a single releasing mechanism is used, as shown in Fig. 12, the construction will be the same as when a plurality of releasing mechanisms are employed. A detailed description of but one of these mechanisms will therefore be given, and the same reference letters will be applied to the different releasing mechanisms shown in the drawings.

The releasing mechanism above referred to comprises a gear wheel e having mounted thereon one or a plurality of members e' adapted to coöperate with an abutment e² carried by the locking member d, said member e' and abutment e² being so constructed as to develop a wedging action as the former passes the latter, such as to impart rectilineal movement to the member d sufficient to disengage it from the plate a. In the form of the invention shown this effect is secured by forming the members e' with an inclined portion e³ terminating in a short flat portion parallel with the face of the gear e of sufficient length to hold the member d retracted for a sufficient interval to permit the rotation of the plate a.

The member e is carried by a sleeve e⁴ mounted upon the shaft f, which is journaled in suitable bearings in the casing A and plate A'. Carried by said shaft f is a spring drum f', the free end of the spring of which is secured to the gear e. Carried by the shaft f is a ratchet wheel f² coöperating with which is a pawl f³. The shaft f is provided

with a knurled head f^4 by means of which the spring of the drum f' may be tensioned, the ratchet mechanism described holding said shaft against return movement under 5 the tension of said spring.

The spring of the drum f' has a normal tendency to rotate the wheel e in a manner to engage the member e' carried thereby with the coöperating abutment e^2 carried by 10 the member d , this tendency being restrained by a gear train connecting the member e with a clock works g , so that the said spring drum can operate on the member e only at certain predetermined intervals.

15 The gear train above referred to comprises the gears h and i mounted upon a shaft j journaled in the casing A and closure plate A' , one end of which projects through said closure plate and is provided with a dial finger j' adapted to indicate upon the graduated dial j^2 how the mechanism is set to operate. The gear h is in constant mesh with the gear e . The gear i is an interrupted or mutilated gear, the portion thereof 20 devoid of teeth permitting the free running of the gear e at the time set for permitting the actuation of the plate a to withdraw the bolts. The gear i is in mesh with a setting gear k carried by a sleeve k' , the end of 25 which is provided with an actuating head k^2 externally of the closure plate A' . The sleeve k' is rotatably mounted upon a shaft m carrying the last gear m' of the train which meshes with a gear of the clock 30 works g .

The sleeve k' is adapted to be disconnected from the shaft m to permit the setting of the lock through the gear k , or to be connected therewith to operatively connect 40 the gear e with the clock works g , by means of a lock nut m^2 carried by said shaft m , and adapted to frictionally engage the head k^2 carried by the sleeve k' . By this construction the lock may be set independently of 45 the clock works.

The spring of the clock works may be tensioned by means of an ordinary key stem g' . When two releasing mechanisms are employed, the locking member d is provided 50 with two abutments e^2 as shown, while, when but one releasing mechanism is used, only one such abutment is provided.

The gear e carries a plurality of indicators n exposed through an opening in the closure plate A' , said indicators bearing the days of the week, or other matter indicating to the user of the lock, conditions about the mechanism.

When using a plurality of members e' , they may be so set as to release the locking member d after similar or dissimilar intervals of time, the adjustment of these members being possible by providing the side of the gear e with spaced screw threaded openings, as shown in Fig. 2 of the drawings.

The operation of the herein described lock is substantially as follows:—

Time locks made in accordance with my invention may be made to a standard design, and any desired variance in the intervals at 70 which the releasing mechanism is to become operative to disengage the lock member d from the plate a , secured by different adjustments in the releasing mechanism, or particularly where long intervals of time are 75 to elapse between the actuation of the releasing mechanism, the lock may be specially designed.

Referring more particularly to the form of the invention shown in Figs. 1, 2 and 5 of the drawings, where two clock works, two releasing mechanisms and a plurality of members e' upon the gear e are used, said members e' will be so spaced apart as to consecutively reach the operative relation to the 80 abutment e^2 coöperating therewith, at intervals of twenty-four hours, providing it is desired to open the safe at such intervals. When access may be had to the knob k^2 of the setting gear, however, this interval may 85 be arbitrarily varied so that a person may vary the time at which the clock may be actuated, from day to day, if it be so desired. Furthermore, if it be desired to prevent the 90 actuation of the lock for a period of more than twenty-four hours, this result may be secured by omitting that member e' which normally would be operative upon the day when it is desired to prevent the lock mechanism being actuated. It would follow, therefore, that the members e' may be so arranged upon the gear e as to secure such an actuation of the lock as would permit the 95 bolts to be withdrawn at varying intervals at the will of the user through the sequential 100 arrangement of said members e' .

When setting the device, the lock nut m^2 is released and the sleeve k' is rotated by means of its knob k^2 , the loosening of the nut m^2 disconnecting said sleeve and its gear 110 k from the gear m' and the clock works.

Assuming that the parts are in the position shown in Figs. 1 and 2, with a wedge member e' just about to engage its coöperating abutment e^2 , the turning of said gear k in the direction of the arrow (Fig. 5) will cause said member e' to recede from its coöperating abutment to an extent determined by the quantity of rotation of said gear. Each of the graduations upon the dial plate j^2 indicates a predetermined time interval, as one hour, so that by setting the dial finger j' at a certain number of graduations from the point at which it is shown upon Fig. 5, will require a corresponding number of 120 hours to elapse before the member e' will again reach the operative relation to its abutment e^2 .

Assuming that it is desired to open the safe after sixteen hours, the finger j' will be 130

set at the sixteenth graduation upon the dial j^2 , moving said finger contra clockwise.

When the releasing mechanism has been so set, the nut m^2 is again tightened, connecting the sleeve k' with the shaft m , thus again connecting the releasing mechanism with the clock works g through the gear m' . The knurled head f^4 of the shaft f^3 is then turned to wind the spring of the drum f' .

10 In withdrawing or retracting the various bolt mechanisms a^4 in opening a door, the plate a will so turn within the limit defined by the slot c' , preventing movement of the locking member d under the control of its 15 spring d' because of the engagement of the end of said member with the plate a at the sides of said slot.

After the lock has been set, the door may be closed and locked at any time by a return 20 movement of said plate a , the locking member d entering the enlarged portion c^2 of said slot substantially simultaneously with the full projection of the bolt mechanisms a^4 .

It will be observed that the gear e and its 25 appurtenances has no function so far as the locking action of the member d is concerned, this gear being totally inoperative and disconnected from the member d at all times excepting that at which the lock is set to 30 permit the actuation of the lock. Any force applied through the stem b to the plate a with an attempt to force the lock, will be transmitted through the member d to its heavy supporting rod c , which possesses 35 sufficient strength to withstand any such stresses.

From the instant the lock nut m^2 is set against the knob k^2 , the gear e will be continuously rotated at low speed through the 40 gear train $h-i-h-m'$, this speed being determined by the clock works g . With a given lapse of time a member e' will approach its coöperating abutment e^2 and at the instant for which the actuation of the 45 releasing mechanism is set, the last gear tooth of the gear i will pass from mesh with the gear k , thus momentarily disconnecting the gear e from the clock works and permitting a limited rotation of said gear e under the control of the spring drum f' , this interval being sufficient to cause the inclined face 50 of the member e' to engage and impart such movement to the member d as will withdraw it from engagement with the plate a . The 55 short surface of the member e' beyond said incline will hold the member d in this position for a length of time determined by the length of this flat portion. The extent of rotative movement of the gear e under the 60 spring drum f' is determined by the length of the mutilated portion of the gear i , the first tooth of said gear beyond said mutilated portion, immediately arresting the movement of the gear e under the control of the 65 drum f' , but continuing the rotation thereof

under the control of the clock works. The resistance encountered by the gear e during its rotation under the spring drum f' , will minimize the force of the impact upon the re-engagement of the teeth of the gear i with 70 the gear k , and relieve the clock works from the effects of any sharp impacts at this time.

During that interval when the member e' is operative to withdraw the member d from its engagement with the plate a , the handle 75 b' may be used to rotate plate to retract the bolts.

As heretofore stated, after the members e' pass out of engagement with their coöperating abutments e^2 , the bolts may be shot and 80 instantly locked through the time lock mechanism, at any time, by merely turning the plate a .

Rectilineal movement of the member d is assured by the use of the rod d^3 which prevents rotation of said member upon the rod c , this construction being used to not only prevent such rotation, but permit the withdrawal of the member d from its engagement with the plate a at any time while access may be had to the lock, the knob d^4 and pin d^5 permitting this member to be held in its withdrawn position so as to prevent the accidental locking of the member a during the time when it is desired to have the door 95 remain open.

To accurately position the abutments e^2 , in the plane of movement of the member or members e' , I provide the plate a adjacent the enlarged portion c^2 of the opening c with 100 a stop plate d^7 adapted to be engaged by the member d after it enters the enlarged portion c^2 of the slot c' .

When a door is closed and locked, the plate a cannot be turned to retract the bolts 105 a^4 until the next member e' becomes operative as to the member d .

By the use of two clock works and two releasing mechanisms, I secure a safeguard against the failure of one of said clock works to properly function. Furthermore, the members e' upon the different gears e may be so positioned that one of them will engage its abutment a short time after the other is timed to engage its abutment, so that in the event of a failure to actuate the plate a when the first abutment disengages the member d therefrom, the user may nevertheless, after a short interval, retract the bolts a^4 when the member e' of the other gear e is operative 110 in relation to said member d .

In the event of external shocks, disarranging the clock works, and thus removing the time control from the gear e , said gear e will turn with great rapidity under the control 115 of the spring drum f' , bringing the members e' into rapid successive operative engagement with the member d . This engagement, however, will be only momentary, so that it would be extremely difficult, if not impos- 120

130

sible, to turn the member *a* to retract the bolts while the member *d* was disengaged therefrom. If it should be sought to apply a continuing pressure upon the handle *b*, so as to take advantage of this momentary disengagement of the member *d*, this pressure would develop sufficient friction between the plate *a* and the member *d*, and between the member *d* and its supporting rod *c*, to arrest rotative movement of the gear *e* by overcoming the tension of the spring of the drum *f*. As a further safeguard, however, the various bolt mechanisms *a* may be controlled by a permutation lock, although this feature is immaterial, and bears no relation to my present invention, which relates merely to the mechanism permitting the actuation of the bolt actuating mechanism only at predetermined intervals.

A time lock mechanism made in accordance with my invention has the advantage of extreme simplicity of construction, which, in a time lock, is desirable.

It is not my intention to limit the invention to the precise details of construction shown in the accompanying drawings, it being apparent that such may be varied without departing from the spirit and scope of the invention.

Having described the invention, what I claim as new and desire to have protected by Letters Patent is:

1. A time lock embodying therein a bolt mechanism, an actuating mechanism therefor including therein a rotatable plate operatively connected with said bolt mechanism, a locking mechanism adapted, when said bolt mechanism is operative, to engage and prevent rotative movement of said plate, a releasing mechanism normally disengaged from, but adapted to engage, said locking member at predetermined intervals and disengage it from said plate, and clock works controlling said releasing mechanism.

2. A time lock embodying therein a bolt mechanism, an actuating mechanism therefor including therein a rotatable plate operatively connected with said bolt mechanism, having a segmental slot therein having an enlargement at one end thereof, a rod passing through said slot, a locking member slidably mounted on said rod and adapted to enter said enlarged portion and prevent movement of said plate, a spring acting on said locking member to normally force it toward said plate, a releasing mechanism embodying therein means adapted at predetermined intervals to disengage said locking member from said plate, and clock works controlling said releasing mechanism.

3. A time lock embodying therein a bolt mechanism, an actuating mechanism therefor including therein a rotatable plate operatively connected with said bolt mechanism,

having a segmental slot therein having an enlargement at one end thereof, a rod passing through said slot, a locking member slidably mounted on said rod and adapted to enter said enlarged portion and prevent movement of said plate, a spring acting on said locking member to normally force it toward said plate, means carried by said locking member whereby, when the lock is accessible, said locking member may be manually disengaged from and held out of engagement with, said plate, a releasing mechanism embodying therein means adapted at predetermined intervals to disengage said locking member from said plate, and clock works controlling said releasing mechanism.

4. A time lock embodying therein a bolt mechanism, an actuating mechanism therefor including therein a rotatable plate operatively connected with said bolt mechanism, a locking mechanism adapted, when said bolt mechanism is operative, to engage and prevent rotative movement of said plate, a releasing mechanism normally disengaged from but adapted to engage said locking member at predetermined intervals and disengage it from said plate, clock works controlling said releasing mechanism, and means whereby said releasing mechanism may be disconnected from said clock works to permit said mechanism to be set independently of said clock works.

5. A time lock embodying therein a bolt mechanism, an actuating mechanism therefor including therein a rotatable plate operatively connected with said bolt mechanism, a locking mechanism adapted, when said bolt mechanism is operative, to engage and prevent rotative movement of said plate, a releasing mechanism including therein a gear wheel, means carried thereby normally disengaged from but adapted to engage said locking member at predetermined intervals and disengage it from said plate, clock works controlling said releasing mechanism, means adapted to actuate said gear wheel independently of said clock works, and a gear train connecting said gear wheel and said clock works embodying therein means whereby, with the initial engagement of the means carried by said gear wheel and said locking member, said clock works will be made temporarily inoperative as to said gear wheel.

6. A time lock embodying therein a bolt mechanism, an actuating mechanism therefor including therein a rotatable plate operatively connected with said bolt mechanism, a locking mechanism adapted, when said bolt mechanism is operative, to engage and prevent rotative movement of said plate, a releasing mechanism including therein a gear wheel, means carried thereby normally disengaged from but adapted to engage said locking member at predetermined intervals

and disengage it from said plate, clock works controlling said releasing mechanism, means adapted to actuate said gear wheel independently of said clock works, a gear 5 train connecting said gear wheel and said clock works embodying therein means whereby, with the initial engagement of the means carried by said gear wheel and said locking member, said clock works will 10 be made temporarily inoperative as to said gear wheel, and means whereby said gear train may be disconnected from said clock works to permit said gear to be set with relation to said locking mechanism independently of said clock works.

7. A time lock embodying therein a bolt mechanism, an actuating mechanism therefor including therein a rotatable plate operatively connected with said bolt mechanism, having a segmental slot therein having an enlargement at one end thereof, a rod passing through said slot, a locking member slidably mounted on said rod and adapted to enter said enlarged portion and prevent 15 movement of said plate, a spring acting on said locking member to normally force it toward said plate, a releasing mechanism embodying therein means adapted at predetermined intervals to disengage said locking member from said plate, clock works controlling said releasing mechanism, and means whereby said releasing mechanism may be disconnected from said clock works to permit said mechanism to be set independently of said clock works.

8. A time lock embodying therein a bolt mechanism, an actuating mechanism therefor including therein a rotatable plate operatively connected with said bolt mechanism, having a segmental slot therein having an enlargement at one end thereof, a rod passing through said slot, a locking member slidably mounted on said rod and adapted to enter said enlarged portion and prevent 20 movement of said plate, a spring acting on said locking member to normally force it toward said plate, a releasing mechanism including therein a gear wheel, means carried thereby normally disengaged from but adapted to engage said locking member at predetermined intervals and disengage it from said plate, clock works controlling said releasing mechanism, means adapted to actuate said gear wheel independently of said clock works, and a gear train connecting said gear wheel and said clock works embodying therein means whereby, with the initial engagement of the means carried by said gear wheel and said locking member, said clock 25 works will be made temporarily inoperative as to said gear wheel.

9. A time lock embodying therein a bolt mechanism, an actuating mechanism therefor including therein a rotatable plate operatively connected with said bolt mechanism,

having a segmental slot therein having an enlargement at one end thereof, a rod passing through said slot, a locking member slidably mounted on said rod and adapted to enter said enlarged portion and prevent 30 movement of said plate, a spring acting on said locking member to normally force it toward said plate, a releasing mechanism including therein a gear wheel, means carried thereby normally disengaged from but adapted to engage said locking member at predetermined intervals and disengage it from said plate, clock works controlling said releasing mechanism, means adapted to actuate said gear wheel independently of said 35 clock works, a gear train connecting said gear wheel and said clock works embodying therein means whereby, with the initial engagement of the means carried by said gear wheel and said locking member, said clock 40 works will be made temporarily inoperative as to said gear wheel, and means whereby said gear train may be disconnected from said clock works to permit said gear to be set with relation to said locking mechanism independently of said clock works.

10. A time lock embodying therein a bolt mechanism, an actuating mechanism therefor including therein a rotatable plate operatively connected with said bolt mechanism, a locking mechanism adapted, when said bolt mechanism is operative, to engage and prevent rotative movement of said plate, a releasing mechanism including therein a gear wheel, means carried thereby normally disengaged from but adapted to engage said locking member at predetermined intervals and disengaged from said plate, clock works controlling said releasing mechanism, a gear train including therein a shaft, a gear carried thereby and rotatable therewith, and constantly in mesh with a gear of said clock works, a sleeve mounted upon said shaft, a gear carried thereby and constantly meshing with a gear in said train to said first named gear wheel, means whereby said sleeve may be manually rotated to set said releasing mechanism independently of said clock works, and means whereby said sleeve may be locked in relation to its shaft to operatively connect said gear wheel with said clock works.

11. A time lock embodying therein a bolt mechanism, an actuating mechanism therefor including therein a rotatable plate operatively connected with said bolt mechanism, a locking mechanism adapted, when said bolt mechanism is operative, to engage and prevent rotative movement of said plate, a releasing mechanism including therein a gear wheel, means carried thereby normally disengaged from but adapted to engage said locking member at predetermined intervals and disengage it from said plate, clock works controlling said releasing mechanism, means

- adapted to actuate said gear wheel independently of said clock works, and a gear train connecting said gear wheel and said clock works embodying therein a mutilated 5 gear whereby, with the initial engagement of the means carried by said gear wheel and said locking member, said clock works will be made temporarily inoperative as to said gear wheel.
- 10 12. A time lock embodying therein a bolt mechanism, an actuating mechanism therefor including therein a rotatable plate operatively connected with said bolt mechanism, a locking mechanism adapted, when said 15 bolt mechanism is operative, to engage and prevent rotative movement of said plate, a releasing mechanism including therein a gear wheel, means carried thereby normally disengaged from but adapted to engage said 20 locking member at predetermined intervals and disengage it from said plate, clock work controlling said releasing mechanism, means adapted to actuate said gear wheel independently of said clock works, a gear train including 25 therein a shaft, a gear carried thereby and rotatable therewith, and constantly in mesh with a gear of said clock works, a sleeve mounted upon said shaft, a gear carried thereby and constantly meshing with a 30 gear in said train to said first named gear wheel, means whereby said sleeve may be manually rotated to set said releasing mechanism independently of said clock works, and means whereby said sleeve may be 35 locked in relation to its shaft to operatively connect said gear wheel with said clock works, said gear train also including therein a mutilated gear whereby, with the initial engagement of the means carried by said 40 gear wheel and said locking member, said clock works will be made temporarily inoperative as to said gear wheel.
13. A time lock embodying therein a bolt mechanism, an actuating mechanism therefor including therein a rotatable plate operatively connected with said bolt mechanism, having a segmental slot therein having an enlargement at one end thereof, a rod passing through said slot, a locking member slidably 45 mounted on said rod and adapted to enter said enlarged portion and prevent movement of said plate, a spring acting on said locking member to normally force it toward said plate, a releasing mechanism including 50 therein a gear wheel, means carried thereby normally disengaged from but adapted to engage said locking member at predetermined intervals and disengage it from said plate, clock work controlling said releasing mechanism, means adapted to actuate said gear wheel independently of said clock works, a gear train including 55 therein a shaft, a gear carried thereby and rotatable therewith, and constantly in mesh with a gear of said clock works, a sleeve mounted upon said shaft, a gear carried thereby and constantly meshing with a gear in said train to said first named gear wheel, means whereby said 60 sleeve may be manually rotated to set said releasing mechanism independently of said clock works, and means whereby said sleeve may be locked in relation to its shaft to operatively connect said gear wheel with said 65 gear in said train.

to said first named gear wheel, means whereby said sleeve may be manually rotated to set said releasing mechanism independently of said clock works, and means whereby said sleeve may be locked in relation to its shaft 70 to operatively connect said gear wheel with said clock works.

14. A time lock embodying therein a bolt mechanism, an actuating mechanism therefor including therein a rotatable plate operatively connected with said bolt mechanism, having a segmental slot therein having an enlargement at one end thereof, a rod passing through said slot, a locking member slidably mounted on said rod and adapted to 75 enter said enlarged portion and prevent movement of said plate, a spring acting on said locking member to normally force it toward said plate, a releasing mechanism including therein a gear wheel, means carried thereby normally disengaged from but adapted to engage said locking member at 80 predetermined intervals and disengage it from said plate, clock work controlling said releasing mechanism, means adapted to 85 actuate said gear wheel independently of said clock works, and a gear train connecting said gear wheel and said clock works embodying therein a mutilated gear whereby, with the initial engagement of the means 90 carried by said gear wheel and said locking member, said clock works will be made temporarily inoperative as to said gear wheel.

15. A time lock embodying therein a bolt mechanism, an actuating mechanism therefor including therein a rotatable plate operatively connected with said bolt mechanism, having a segmental slot therein having an enlargement at one end thereof, a rod passing through said slot, a locking member slidably mounted on said rod and adapted to enter said enlarged portion and prevent movement of said plate, a spring acting on said locking member to normally force it toward said plate, a releasing 100 mechanism including therein a gear wheel, means carried thereby normally disengaged from but adapted to engage said locking member at predetermined intervals and disengage it from said plate, clock work controlling said releasing mechanism, means adapted to actuate said gear wheel independently of said clock works, a gear train including 105 therein a shaft, a gear carried thereby and rotatable therewith, and constantly in mesh with a gear of said clock works, a sleeve mounted upon said shaft, a gear carried thereby and constantly meshing with a gear in said train to said first named gear wheel, means whereby said 110 sleeve may be manually rotated to set said releasing mechanism independently of said clock works, and means whereby said sleeve may be locked in relation to its shaft to operatively connect said gear wheel with said 115 gear in said train.

clock works, said gear train also including therein a mutilated gear whereby, with the initial engagement of the means carried by said gear wheel and said locking member, 5 said clock works will be made temporarily inoperative as to said gear wheel.

16. A time lock embodying therein a bolt mechanism, an actuating mechanism therefor including therein a rotatable plate operatively connected with said bolt mechanism, a rod adjacent said plate, a non-rotatable locking member slidably mounted on said rod and adapted to operatively engage and prevent movement of said plate, a spring 10 acting on said locking member to normally force it toward said plate, a releasing mechanism including therein a gear wheel, coöperating members carried by said locking member and said gear wheel respectively, 15 one of said coöperating members having an inclined surface presented toward the other, whereby at predetermined intervals said locking member will be disengaged from said plate, clock works, and 20 a gear train connecting said clock works and said gear wheel.

17. A time lock embodying therein a bolt mechanism, an actuating mechanism therefor including therein a rotatable plate operatively connected with said bolt mechanism, a rod adjacent said plate, a non-rotatable locking member slidably mounted on said rod and adapted to operatively engage and prevent movement of said plate, 30 a spring acting on said locking member to normally force it toward said plate, a releasing mechanism including therein a gear wheel, a plurality of wedge-like members removably mounted upon said gear wheel, an 35 abutment carried by said locking member and adapted to be successively engaged by said wedge-like member, whereby at predetermined intervals said locking member will be disengaged from said plate, clock 40 works, and a gear train connecting said clock works and said gear wheel.

18. A time lock embodying therein a bolt mechanism, an actuating mechanism therefor including therein a rotatable plate operatively connected with said bolt mechanism, a rod adjacent said plate, a non-rotatable locking member slidably mounted on said rod and adapted to operatively en- 50

gage and prevent movement of said plate, a spring acting on said locking member to normally force it toward said plate, a releasing mechanism, two gear wheels, a plurality of wedge-like members removably mounted upon each of said gear wheels, two abutments upon said locking member adapted to be engaged by the wedge-like members upon said wheels respectively, two clock works, gear trains connecting said clocks with said gears respectively, and means whereby said gear wheels may be disconnected from said clock works to permit said releasing mechanism to be set to cause said wedge-like members, at predetermined intervals, to engage said abutments simultaneously or successively, and disengage it from 60 said plate.

19. A time lock embodying therein a bolt mechanism, an actuating mechanism therefor including therein a rotatable plate operatively connected with said bolt mechanism, a locking mechanism adapted, when said bolt mechanism is operative, to engage and prevent rotative movement of said plate, a releasing mechanism including therein a gear wheel, means carried thereby normally 75 disengaged from but adapted to engage said locking member at predetermined intervals and disengage it from said plate, clock works controlling said releasing mechanism, a spring drum operative upon said 80 gear wheel and tending to normally rotate it independently of said clock works, means whereby the spring of said drum may be wound, and a gear train connecting said gear wheel and said clock works embodying 85 therein a mutilated gear, whereby with the initial engagement of the means carried by said gear wheel and said locking member, said gear train will be disconnected from said clock works, and permit said gear 90 wheel to be momentarily actuated by said spring drum.

In witness whereof I have hereunto affixed my signature, in the presence of two subscribing witnesses, this 27th day of Sept. 100 1919.

AMEDEO A. MANCINI.
